RECEPTACLE FOR TOOTHBRUSHES

Filed Sept. 13, 1928

UNITED STATES PATENT OFFICE

HORACE E. BARKER, OF BROOKLYN, NEW YORK

RECEPTACLE FOR TOOTHBRUSHES

Application filed September 13, 1928. Serial No. 305,658.

This invention relates to a receptacle adapted to contain a toothbrush and its appurtenances.

An object of the invention is to provide a simple, inexpensive and compact receptacle of such construction that the handle of the contained toothbrush (or analogous implement) constitutes an efficient closure for the receptacle.

Another object is to provide for such receptacle a wall of thin transparent celluloid, or similar material, which is firmly and rigidly supported.

A further object is to provide a receptacle which can be readily opened to expose the contents thereof in a manner to facilitate their easy removal and replacement.

With these and other objects in view my invention comprises a receptacle for a toothbrush, &c., embodying novel features of construction and combinations of parts which will be hereinafter described and claimed.

In the drawings—

Figure 1 is a perspective of a receptacle embodying a preferred form of my invention.

Fig. 2 is a similar view showing the hinged wall open.

Fig. 3 is a view similar to Fig. 2, showing the device as containing a toothbrush and allied articles.

Fig. 4 is a transverse section through the closed receptacle and the head of the contained toothbrush.

Fig. 5 is a similar section through the receptacle and a rubber massaging device underlying the handle of the contained brush.

Referring to the drawings, 10 designates a relatively thin metal base strip having upwardly extending end portions 11, 12 terminating in inturned lips 13. The width of this strip slightly exceeds that of the handle including the back of the toothbrush to be enclosed; the distance between the upper surface of the strip and the under surfaces of the lips is substantially equal to the depth of the brush head, and the distance between the inner walls of the ends 11, 12 corresponds substantially to the length of the brush handle and head.

The elongated base strip has struck there-

from in spaced relation to the end portion 11 an upstanding tongue 14 which, in conjunction with such end, affords a space adapted to receive the brush head the bristles whereof rest upon the base strip while the handle, including the brush back, extends between the two end portions 11, 12 and is held in place by the overhanging lips 13. Preferably the base strip has cemented thereto a protective covering 15 of celluloid which effectually closes the opening resulting from the formation of the tongue 14, and preferably also a teat 130 is punched below the lip 13 of the end 12 in a position to aid in supporting the adjacent end of the handle.

At one edge of the base strip, throughout its length, is a fixed side wall comprising preferably an open rectangular metal frame 16 to which are cemented the margins of a thin sheet of celluloid 17, which frame is secured to inturned lips 18 integral with the adjacent vertical edges of the upstanding ends. The frame 16 effectually reinforces the celluloid, thus enabling the economical use of extremely thin material. Hingedly mounted, as at 19, on the opposite edge of the strip is a rigid side plate 20 of celluloid or other material which also extends throughout the length of the strip and is movable to vertical or horizontal position relative to the strip.

When the plate 20 is in vertical or closed position its ends bear tightly against the opposing end walls 11, 12, thus maintaining the plate in parallel relation to the fixed wall 16, 17. The plate affords in conjunction with the latter and with the base strip 10 and ends 11, 12, a compact receptacle for the brush, the handle whereof, being snugly embraced by the upper longitudinal edges of the fixed and movable walls, constitutes, in effect, the top of the receptacle. The upper edge of the side frame 16 and the corresponding edge of the side wall 20 are preferably formed with suitably disposed inturned lips 21, 22, respectively, which conform to and are adapted frictionally to engage the incurved edge portions 23 of the brush handle H, thus closing the gaps at such

portions and serving to maintain the toothbrush in place.

- The space beneath the handle of the brush is utilized for the reception of dental accessories, and to that end a suitably disposed tongue 24, similar to the tongue 14, is preferably struck up from the base strip to afford appropriate compartments. When the receptacle is used for a toothbrush having interchangeable heads, such as a brush head 25 and rubber massaging heads 26, one of the compartments affords a convenient receptacle for a supply of the latter and the other compartment for the reception of dentifrice. As seen in Fig. 3 the handle proper is provided at its inner end with a longitudinally split tang 27 which may be forcibly inserted in a suitable opening in the brush head or in a massaging head. The inner side of the hinged wall 20 is preferably provided with parallel longitudinal ribs or lips 28 adapted to support dentifrice 29 in convenient position for use in conjunction with the toothbrush when the receptacle is open, which dentifrice is preferably in cake or tablet form. When the receptacle is closed the dentifric is confined within the adjacent compartment afforded below the handle of the contained brush. From the foregoing it will be seen that my invention provides a simple, inexpensive, durable and compact trough-like receptacle wherein the handle of a toothbrush constitutes an efficient closure for the top of the receptacle, and wherein by the simple act of opening the hinged side wall 20, the toothbrush and the contents of the receptacle are fully exposed in such a way that they can be severally removed with facility for use. Further, the brush, &c., can be as readily replaced in the receptacle and the latter be effectually closed.

My invention is not limited to the exact details of construction herein disclosed, as the elements may be modified within the principles of my invention and the scope of the appended claims.

I claim:

1. A receptacle for toothbrushes and the like, comprising an elongated base strip, upstanding ends, and two spaced-apart side walls whereof one wall is fixed and the other wall is hinged in respect to the base strip, the whole forming, when the hinged wall is closed, a trough-like container for a toothbrush whereof the handle including the back of the brush head extends between the ends and is snugly embraced throughout its length by the upper edges of the side walls, the space beneath said handle affording a closed article receiving chamber.

2. A receptacle for toothbrushes and the like, comprising an elongated base strip, upstanding ends terminating in inwardly projecting handle retaining portions, and two-

spaced-apart side walls whereof one wall is fixed and the other wall is hinged in respect to the base strip, the whole forming, when the hinged wall is closed, a trough-like container for a toothbrush whereof the handle including the back of the brush head extends between the ends and below the retaining portions and is snugly embraced throughout its length by the upper edges of the side walls, the space beneath said handle affording a closed article receiving chamber.

3. A receptacle for toothbrushes and the like, comprising an elongated base strip having upstanding end portions and having also an upstanding partition in spaced relation to one of said ends, two spaced-apart side walls whereof one wall is fixed and the other wall is hinged in respect to the base strip, the whole forming, when the hinged wall is closed, a trough-like container for a toothbrush whereof the head is confined in the space between the partition and the adjacent end portion while the handle including the back of the brush head extends between the two end portions and is snugly embraced throughout its length by the upper edges of the side walls, the space beneath said handle affording a closed article receiving chamber.

4. A receptacle for toothbrushes and the like, comprising an elongated base strip, upstanding ends, and two spaced-apart side walls whereof one wall comprises a rectangular open metal frame supporting a thin sheet of celluloid and fixed in respect to the base strip and the other wall is hinged in respect to the strip, the whole forming, when the hinged wall is closed, a trough-like container for a toothbrush whereof the handle including the brush head extends between the ends and is snugly embraced throughout its length by the upper edges of the side walls, the space beneath said handle affording a closed article receiving chamber.

5. A receptacle for toothbrushes and the like, comprising an elongated base strip, upstanding ends, and two spaced-apart side walls having inwardly extending lateral lips at their upper edges one of said walls being fixed and the other wall being hinged in respect to the base strip, and the whole forming, when the hinged wall is closed, a trough-like container for a toothbrush whereof the handle including the brush head extends between the ends and is snugly embraced throughout its length by the upper edges including the lateral lips of the side walls, the space beneath said handle affording a closed article receiving chamber.

6. A receptacle for toothbrushes and the like, comprising an elongated base strip, upstanding ends, and two spaced-apart side walls whereof one wall is fixed and the other wall is hinged in respect to the base strip, said hinged wall being provided on its in-

ner surface with means for supporting dentifrice, and the said strip, ends and walls forming, when the hinged wall is closed, a trough-like container for a toothbrush whereof the handle including the brush head 5 extends between the ends and is snugly embraced throughout its length by the upper edges of the side walls, the space beneath said handle affording a closed chamber adapted to receive the dentifrice supported on 10 the hinged wall.

Signed at New York in the county and State of New York this 11th day of September A. D. 1928.

HORACE E. BARKER.
